RESILIENT CUSHION INSERT

Fred L. Haushalter, Pontiac, Mich.

Application January 15, 1957, Serial No. 634,221

3 Claims. (Cl. 287—126)

The invention relates to a resilient cushion inserts and forms a continuation-in-part of my former application for patent Serial No. 542,354, filed October 24, 1955. In the said application a method is described for introducing into a recess within a rigid member a resilient insert of rubber-like material which in unstressed condition is of a transverse dimension greater than that of the recess in which it is inserted. Thus, when in place it has a tendency to expand, exerting a strong pressure against the walls of the recess so as to be frictionally retained therein and without the necessity of vulcanization or other attachment to said walls. The subject matter of the present case is a structure having such insert, one specific example of which is a track shoe for an endless track type tractor. An essential feature as above stated is that the insert when unstressed is of a greater transverse dimension than that of the recess. There are, however, other advantageous features of this structure as hereinafter set forth.

In the accompanying drawings:

Figure 1 is a cross section on line 1—1 of Figure 4 through a recessed rigid body having a prestressed rubber-like insert therein.

Figure 2 is a cross section illustrating one method of installing the insert within the rigid body and simultaneously pretensioning the same.

Figure 3 is a similar view showing a slightly modified construction.

Figure 4 is an elevation partly in section of a track bar for an endless track type tractor having a resilient cushion insert therein.

Figure 5 is a bottom plan view of one of the shoes of a modified type of endless track tractor having a pair of cushion inserts therein.

Figure 6 is a cross section on line 6—6 of Figure 5.

Figure 7 is a section similar to Figure 1 showing a modified construction.

Figure 8 is a cross section somewhat similar to Figure 3 but illustrating another modification.

Figure 9 is a view showing the manner of introducing the insert of Figure 8 in its recess.

Figure 10 is a sectional elevation similar to Figure 4 showing another modification.

While there are many specific constructions in which a resilient insert of my improved construction would be advantageous, I shall describe specifically only its application to a tractor shoe. It has been the practice in the past to vulcanize the rubber-like insert to the walls of the recess which adds a considerable item to the cost of manufacture. Also, shrinkage of the insert by cooling after vulcanization is detrimental. Both of these detrimental features are avoided with my construction, which is as follows:

As shown in Figure 1 the rigid member A is of U-shaped cross section to form a channel-shaped recess within which is placed the elongated resilient insert B. Figure 2 shows the insert B as originally of greater cross-sectional width than the recess within the mem-

2

ber A. Such insert B is also provided centrally with a longitudinally extending thin slot B' which extends in depth from its read edge to within a short distance of its forward edge which as indicated at B² is rounded. 5 C is a thin plate-like rigid member within the slot B' extending rearward beyond the same. Thus pressure applied on the outer end of the member C will, as above stated, force the insert edgewise into the recess and at the same time stretch it so as to reduce its width. Figure 3 10 shows a modified construction in which the insert D has a pair of spaced slots D', D² extending therein on opposite sides of the center thereof. The rigid member E has corresponding spaced thin plate-like rigid portions E' and E² for engaging said slots. This will afford 15 a more stable construction than that illustrated in Figure 2 for forcing the insert into the recess. With both constructions the insert will be stretched sufficiently to reduce its width to that of the recess and after complete insertion the rigid members C and E may be withdrawn, whereupon contraction of the stretched member 20 will close the slots B' and D', D².

However, the contraction in stretched length required for closing the slots is less than the total stretching during insertion so that the insert is still under stress tending 25 to expand the same transversely. This will insure sufficient frictional contact between the insert and the walls of the recess to retain the former without the necessity of vulcanization. As the pressure of the member E is applied to the central portion of the insert and as the 30 side portions thereof are retarded by friction with the walls of the recess, this central portion will be advanced to a greater degree than the side portions. This would result in concaving the outer end of the insert and to avoid such result the central portion is originally extended rearward beyond the side portions. Thus the 35 portion of the insert between the slots D', D² projects rearward at D³ beyond the portions outside of said slots. During insertion of the member D the friction of the spaced portions E' and E² of the member E on the central 40 portion of the insert which is therebetween will draw this projecting portion D³ inward so that its rear end will be more nearly in line with the side portions.

Figure 4 is a sectional elevation of one of the transversely extending track bars of an endless track type tractor and of which Figure 1 is a cross section. It will be noted that the bar A is of inverted U-shape cross section throughout its length but that the vertical depth in the central portion A' of the bar is greater than in the end portions A² and A³ thereof. The insert B also extends the full length of the bar and is fashioned to correspond in depth to the portions A', A² and A³ thereof. It is also provided with one or more longitudinally extending slots such as B', Figure 2, or D', D², Figure 3 which slots extend in depth from the lower edge of the 55 insert to within a short distance from the upper edge thereof. Rigid members such as C or E engage these slots and form the means for prestretching the insert and engaging the same with the bar as above described. When these rigid members are withdrawn the insert will still be retained by the resilient stresses remaining therein.

The construction illustrated in Figures 5 and 6 is of a track shoe F having spaced projecting lugs F', F² and F³ at one edge thereof and spaced lugs F⁴ and F⁵ projecting from the opposite edge for engaging the spaces between 65 the aforesaid lugs in the next adjacent shoe and pivotally connected thereto. As heretofore constructed, these shoes are formed with triangular recesses in their surfaces for receiving rubber inserts vulcanized to the metal of the shoe. I have changed the construction by forming channel recesses each with parallel side walls and adjacent respectively with opposite oblique sides of the triangle extending to a common apex. These channels 70

can either be formed in the original casting or, as shown, by spaced bars G and G' welded to the casting. Cushion inserts H of resilient rubber-like material are inserted edgewise within said channels by the method above described and by the use of thin rigid members which are in slots extending the full length of said members. Thus, the resilient stresses within the insert tending to expand it transversely will so increase the friction with the walls of the recess as to retain the insert without the necessity of vulcanization. Similar prestretched inserts may be placed in recesses in the top of the shoe, as indicated at I and I'.

For some uses it may be desirable to provide the walls of the recess with one or more inwardly projecting lugs which will be embedded in the insert and will assist in retaining the same. Such a construction is shown in Figure 7 in which the member A has portions J and J' thereof struck inward from opposite walls to form said lugs. The insert B may be installed by the method previously described during which the lugs J and J' will become embedded in the rubber.

As thus far described the rigid member which is used for stretching the insert to reduce its width is later withdrawn from its slot which will be closed by the resiliency of the insert material. It may, however, be desirable to leave one or more of these rigid members permanently within the resilient insert, such for instance as shown in Figure 8. Here the spaced thin rigid members E³ and E⁴ remain within the insert D⁴ and also have portions E⁵ which project outward beyond the insert. The manner of installing the insert is illustrated in Figure 9 where the projecting portions E⁵ of the members E³ and E⁴ are first engaged with slots in a head member E⁶ by which they are impelled to stretch the insert and force it within the recess. If desired, a pin E⁷ may be used for locking the head E⁶ to the members E³ and E⁴ during installation, said pin being later removed for detachment of the head. The projecting portions E⁵ will add to the traction in soft ground. Also, they may be useful in amphibious vehicles for propelling them through the water. Where the rigid members are to be left permanently in the insert it is preferable that they should be formed of tempered or hardened metal.

As shown in Figure 10 the projecting portion of the resilient insert B is corrugated, as indicated at E⁸.

What I claim as my invention is:

1. A rigid member having a recess therein with spaced walls in fixed relation to each other, and an elongated compressed insert of rubber-like material disposed edgewise forwardly within a projecting edgewise rearwardly and outwardly of said recess, said insert originally having a pair of spaced, narrow slots intermediate said walls dividing the rearward end of said insert into a central portion and adjacent side portions, said slots extending into said insert from the rearward edge thereof to within

a short distance of the opposite forward edge of the insert, said central portion defined by said slots extending rearwardly from the rearward edge of the side portions, the original width of said insert being greater than the distance between said spaced walls, said side portions being stretched into said recess in the direction of the forward edge thereof while said central portion remains unstretched, whereby, when stretching force is terminated, the outer surface of said central portion is substantially flush with the outer surfaces of the adjacent side portions of the insert and the insert is under compression and in frictional engagement with said walls.

2. The combination set forth in claim 1 further characterized in that the side walls of the recess are parallel and the slots are parallel to said side walls and to each other.

3. A rigid member having a recess therein with spaced walls in fixed relation to each other, an elongated compressed insert of rubber-like material disposed edgewise forwardly within and projecting edgewise rearwardly and outwardly of said recess, said insert originally having a pair of spaced narrow slots intermediate said walls dividing the rearward end of said insert into a central portion and adjacent side portions, said slots extending into said insert from the rearward edge thereof to within a short distance of the opposite forward edge of the insert, said central portion defined by said slots extending rearwardly from the rearward edge of the side portions, the original width of said insert being greater than the distance between said spaced walls, a pair of rigid forcing blades inserted in said slots, said blades forming the means for stretching said insert into said recess, said side portions being stretched into said recess in the direction of the forward edge thereof while said central portion remains unstretched, whereby, when stretching force is terminated, the outer surface of said central portion is substantially flush with the outer surfaces of the adjacent side portions of the insert and the insert is under compression and in frictional engagement with said walls and said blades, said blades thereafter forming part of the assembly.
